FURNACE

Original Filed March 23, 1927 3 Sheets-Sheet 3

UNITED STATES PATENT OFFICE.

GEORGE HOFMANN, OF LYONS, ILLINOIS.

FURNACE.

Application filed March 23, 1927, Serial No. 177,598. Renewed December 6, 1928.

My invention relates generally to furnaces, though more particularly, to oil-fired furnaces, it being my primary object to provide improvements in furnaces to the end 5 that the maximum efficiency of the fuel introduced into the furnace may be obtained, the discharge of unconsumed free carbon from the combustion chamber and the deposit of such carbon on the heating surfaces 10 of the furnace be prevented, and the heat units generated by the combustion of the fuel, particularly in the heating of water in a boiler furnace, be utilized to as near the maximum extent as possible.

Referring to the accompanying drawings:—

Figure 1 is a view in front elevation of a boiler furnace constructed in accordance with my invention, a portion of the front 20 thereof being broken away to disclose interior details. Fig. 2 is a view in side elevation of the furnace with a portion of the side thereof broken away to disclose interior details, the lower portion of the furnace 25 being shown in section with the section taken at the line 2—2 on Fig. 3 and viewed in the direction of the arrows. Fig. 3 is a plan sectional view taken at the irregular line 3—3 on Fig. 2 and viewed in the direction of the arrows; and Fig. 4, an enlarged, 30 broken sectional view taken at the line 4—4 on Fig. 2 and viewed in the direction of the arrows.

As a preface to the following description, 35 it may be stated that my present invention relates generally to the provision of a deflector located in the rear portion of the combustion chamber and preferably adjustable lengthwise of the chamber for impingement by the combustion-mixture in its travel toward the stack and the deflecting of such mixture forwardly into the main body of flame to effect the complete combustion of the fuel and the elimination of free carbon, 40 my invention having been devised for use more particularly, though not to its exclusion in other structures, in connection with an oil-fired furnace involving a supplemental water heating chamber located adjacent the burner and provided with means

whereby the stream of burning mixture is caused to be deflected laterally in both directions and thereafter rise about the opposite sides of the supplemental water chamber in accordance with my pending application for U. S. patent on furnaces, Serial 55 No. 162,066, filed January 19, 1917, and I have, therefore, chosen to illustrate it in such a construction of furnace, but without, however, intending to limit the invention to 60 its use in such a structure.

The particular furnace structure shown is generally of the separate water-chamber steam-boiler type presenting a combustion chamber 10 containing an opening in the 65 front wall of the furnace equipped with a door 11, and an outlet 12, for the products of combustion, in the rear wall of the furnace adjacent the top of the chamber 10. The water chambers referred to and represented 70 at 13 are formed in the several flatwise-assembled grid-like sections 14 of the furnace the chambers in which open, respectively, into pipes 15 communicating with a header 15^a from which the steam pipe 16 extends. 75 The lower ends of the sections 14 form the upper portion of the combustion chamber 10, the intermediate ones of these sections having leg-portions 13^a which form portions 80 of the side walls of the combustion chamber 80 10, as shown in Fig. 1, with the water-chambers in these sections extending downwardly close to the bottom surfaces of these legs. The sections 14 are shown as supported on a rectangular base 17 of concrete 85 which forms the lower portions of the surrounding walls of the combustion chamber 10, the opposite side walls of this chamber from the bottom of the furnace to a point about half way to the top of this chamber, 90 and preferably throughout the length of the latter, being of upwardly and outwardly curved form, as illustrated at 18, such surfaces being preferably provided by lining 95 the side walls of the base 17 with refractory material 19 as shown.

Located in the combustion chamber 10 in a position to extend into the path of the combustion mixture in flowing in the combustion chamber is a combustion mixture de- 100

flecting and primary water-heating device represented generally at 20 which extends lengthwise of the chamber 10 and at its sides, top and bottom, in spaced relation to 5 the opposing surfaces of this chamber, the front-end portion of the device 20 being in line with the inlet 21 through which the combustion-mixture, as for example atomized oil, is introduced into the combustion 10 chamber 10, the mixture burning upon issuing from the inlet and it moves along the deflector-device 20.

The device 20, which in the particular arrangement shown, is provided as a structure 15 separate from the furnace proper, and would be so provided especially when it is desired to equip existing furnaces with such a structure, but which in the case of original installations could be built into the furnace otherwise than as a separate part, is formed of a 20 hollow body 22 of general semi-cylindrical form, with its curved surface uppermost, as shown, and arranged in the chamber 10 to extend substantially horizontal therein, the 25 body 22 having a depending hollow fin 23, the space in which opens into the space within the body 22 thereby forming a water chamber in the body 22 which extends downwardly into the fin 23 throughout substantially the length of the latter.

The fin 23 which is disposed substantially 30 vertically and is located midway between the opposite sides of the body 22, inclines at its bottom edge portion upwardly and rearwardly as shown, the forward extremity of the fin, which is in direct alignment with the fuel inlet 21, being relatively thin and presenting substantially parallel vertical side 35 surfaces 25. The side surfaces of the fin, from the front end thereof toward the rear end are outwardly curved, as represented at 40 24, with progressively increasing curvature to a point at the extreme rear end of the fin 23 where the fin substantially merges 45 into the flat horizontal bottom of the body portion 22.

The water chamber in the device 20 is connected at its forward end with a pipe 26 50 constituting a part of the piping through which the water condensed in the heating pipes of the heating system in connection with which the boiler would be used, is returned to the boiler, the pipe 26 being shown as connected at 27 with piping 28 which 55 opens into the lower ends of the legs of the water-chamber sections 14, through headers 29 having branch pipes 30; one of the headers 29 connecting with a pipe 31 through which the return water flows into one of the 60 headers 29 and thence into the legs of the water-chamber sections at both sides of the furnace and into the forward end of the chamber in the device 20. The rear end of the water chamber in the device 20 communicates, at its upper portion, with one end 65

of a pipe 32 which opens at its other end into the water chamber in one of the sections 14 preferably below the water level maintained in the boiler.

The combustion chamber also contains hollow cylinders 33 located at opposite sides of the device 20 and closely adjacent, but spaced from, the sides of the latter, these cylinders which incline upwardly toward the rear of the furnace, as shown, being located in the same horizontal plane as that occupied by the device 20, the opposite ends of these cylinders being connected with pipes 34 which open into the water chambers in the legs of certain of the sections 14 as illustrated in the drawings.

The construction shown also involves deflector means for the combustion-mixture embodying my invention, these deflector means according to the particular illustrated embodiment of the invention comprising a curved plate 35 located between the rear end of the device 20 and the rear wall of the combustion chamber 10. The lower portion of this plate, which is shaped to conformingly fit the side walls of the lower portion of the combustion chamber, extends at its lower edge close to, and preferably bears against, the bottom of this chamber. The lateral edge portions of the upper portion of the deflector plate 35 which extends at its forward extremity a considerable distance above the device 20, are preferably curved inwardly and forwardly, as shown and extend relatively close to the adjacent portions of the side walls of the chamber 30.

The deflector plate 35 is preferably supported in a manner to permit it to be adjusted lengthwise of the combustion chamber toward and away from the device 20 as for example by providing slideways 36 on the refractory material 19 at opposite sides of the combustion chamber, with guides 37 extending above, and vertically spaced from, the ways 36, the plate 35 bearing upon the slideways 36 at shoulder, or shoe-portions 38 secured to the plate 35 and extending laterally therefrom at opposite edges of the latter and located beneath the guides 37.

As a convenient means of adjusting the deflector back and forth in the combustion chamber the plate 35 may be provided with eyes 39 for engagement with the hook-ends of rods (not shown) which may be introduced into the combustion chamber from its forward end through an opening in the front wall of the combustion chamber and covered by a removable closure 40, and hooked into these eyes.

In the operation of the structure shown the combustion mixture discharges into the combustion chamber 10 through the inlet 21, the mixture being ignited as it leaves the inlet, and by reason of the position of the fin 23 directly in line with the inlet, is caused to be

divided by the fin into two separate streams which upon traversing the increasingly curving side-surfaces of the fin are deflected laterally and outwardly towards opposite sides 5 of the combustion chamber and thereafter flow toward the median line of the device 20 and thence rearwardly into engagement with the deflector 35 with the result that the stream of combustion-mixture is deflected 10 forwardly into a position above the body of flame rising from around the device 20 thereby causing such portions of the combustion-mixture which are unburned before impinging against the deflector, to be subjected to 15 the intense heat of the main body of flame and thereby become consumed with the manifest advantage.

Furthermore, the deflection of the burning mixture as stated serves to concentrate the 20 heat of the burning mixture against the member 20 and also against the lower portions of the legs of the water-chamber sections and against the water-cylinders 33 resulting in the utilization, to the maximum 25 extent, of the fuel for heating the water in the boiler structure.

The feature of providing for the adjustment of the deflector 35 as stated is of particular advantage as it permits of the positioning of the deflector for functioning to the best advantage under the varying conditions presented in furnace structures, this being particularly true where the furnace is of the oil-burning type.

It will be observed that my improvement does not involve the baffling of the stream of burning combustion-mixture but the deflecting thereof by means of the provision of a curved surface against which the stream of 35 burning mixture flows and by which its course is changed to direct it backwardly without abrupt arrestation.

While my improvements were devised for use more particularly in a furnace having the auxiliary water containers as above described, and in connection with which it functions in a highly efficient manner, it will be understood that it is not limited to use in a furnace of the type shown, nor one employing auxiliary heating chambers, nor oil as the fuel, neither is it limited to the provision of deflector means of the particular construction shown, and therefore I do not wish to be understood as intending to limit it to use 50 in the connection shown or in the form illustrated and described.

What I claim as new, and desire to secure by Letters Patent, is:

1. A furnace comprising a combustion chamber, a water-container in said chamber, means for directing a combustion mixture against said container, and a deflector at the rear end portion of said chamber and extending crosswise thereof and arranged to 60

flect the mixture forwardly and over said water-container.

2. A furnace comprising a combustion chamber, a water-container in said chamber, means for directing a combustion mixture 70 against said container, and a deflector at the rear end portion of said chamber and extending crosswise thereof, said deflector extending from a point adjacent the floor of said combustion chamber and below said 75 water-container to a point above said water-container.

3. A furnace comprising a combustion chamber, a water-container in said chamber, means for directing a combustion mixture 80 against said container, and a deflector at the rear end portion of said chamber and extending crosswise thereof, said deflector extending from a point adjacent the floor of said combustion chamber and below said 85 water-container to a point above said water-container, with its front face curving forwardly at its upper and lower portions.

4. A furnace comprising a combustion chamber, a water-container in said chamber, 90 supplemental water-containers in said chamber at the sides of said first-referred-to container, means for directing a combustion mixture against said containers and a deflector at the rear end portion of said chamber 95 and extending crosswise thereof and arranged to deflect the mixture forwardly and over said water-containers.

5. A furnace comprising a combustion chamber, means for directing a combustion 100 mixture into the front end of the combustion chamber, a deflecting member in said chamber arranged to deflect the mixture laterally in both directions, and a second deflector at the rear end portion of said chamber and extending crosswise thereof and arranged to 105 deflect the mixture, deflected by said first-named deflector, forwardly and over the flame rising upwardly around the latter.

6. A furnace comprising a combustion 110 chamber, means for directing a combustion mixture into the front end of the combustion chamber, a combined water container and fuel deflecting member in said chamber arranged to deflect the combustion mixture 115 laterally in both directions, and a second deflector at the rear end portion of said chamber and extending crosswise thereof and arranged to deflect the combustion mixture, deflected by said first-named 120 deflector, forwardly and over the flame rising upwardly around the latter.

7. A furnace comprising a combustion chamber, a deflector located in said chamber, means for supplying a combustion mixture to said chamber and causing it to flow substantially horizontally therein, the longitudinal axis of said deflector extending generally in the direction of said flow of the combustion mixture, said deflector having 125 130

an under-surface disposed in the line of said flow and so shaped as to cause the mixture engaging said deflector to be deflected laterally in opposite directions toward the side walls of said chamber, and a second deflector at the rear end portion of said chamber and extending crosswise thereof and arranged to deflect the mixture, deflected by said first-named deflector, forwardly and over the flame rising upwardly around the latter.

8. A furnace comprising a combustion chamber having upwardly and outwardly curved side walls, means for supplying a combustion mixture to said chamber and causing it to flow substantially horizontally therein, means extending into the line of flow of the mixture for deflecting the mixture laterally outwardly toward and against said curved side walls, and a deflector at the rear end portion of said chamber and extending crosswise thereof and arranged to deflect the mixture, deflected by said second-named means, forwardly and over the flame rising upwardly around the latter.

9. A furnace comprising a combustion chamber having upwardly and outwardly curved side walls, a deflector in said chamber, means for supplying a combustion mixture to said chamber and causing it to flow substantially horizontally therein, the longitudinal axis of said deflector extending generally in the direction of said flow of the combustion mixture, said deflector having an under-surface disposed in the line of said flow and so shaped as to cause the mixture engaging said deflector to be deflected laterally outwardly in opposite directions toward and against said curved side walls, and a second deflector at the rear end portion of said chamber and extending crosswise thereof and arranged to deflect the mixture, deflected by said first-named deflector, forwardly and over the flame rising upwardly around the latter.

10. A furnace comprising a combustion chamber having upwardly and outwardly curved side walls, means for supplying a combustion mixture to said chamber and causing it to flow substantially horizontally therein, a combined water container and fuel deflecting member extending into the line of flow of the mixture and adapted to deflect the mixture laterally outwardly toward and against said curved side walls, and a second deflector member at the rear end portion of said chamber and extending crosswise thereof and arranged to deflect the mixture, deflected by said first-named deflector, forwardly and over the flame rising upwardly around the latter.

11. A furnace comprising a combustion chamber, means for supplying a combustion mixture to said chamber and causing it to

flow substantially horizontally therein, a deflecting member in said chamber arranged to deflect said mixture laterally in both directions, and a second deflector at the rear end portion of said chamber and extending crosswise thereof and arranged to deflect said mixture, deflected by said first-named deflector, forwardly and over the flame rising upwardly around the latter, the upper portion of said deflector curving toward the front of said chamber with its lateral edge portions deflected forwardly.
